D. O. SHIBLER

ICE CREEPER

Filed Jan. 5, 1925

Patented Sept. 8, 1925.

1,552,512

UNITED STATES PATENT OFFICE.

DAVID O. SHIBLER, OF HANOVER, OHIO.

ICE CREEPER.

Application filed January 5, 1925. Serial No. 574.

To all whom it may concern:

Be it known that I, DAVID O. SHIBLER, a citizen of the United States, residing at Hanover, in the county of Licking and State of Ohio, have invented certain new and useful Improvements in Ice Creepers, of which the following is a specification.

This invention relates to ice creepers for use on the heels of boots and shoes; and it consists in the novel construction and combination of the parts hereinafter fully described and claimed which enable it to be readily attached to and detached from the shoe heel.

In the drawings, Figure 1 is a side view of an ice creeper constructed according to this invention. Fig. 2 is a plan view of the same. Fig. 3 is a side view similar to Fig. 1, but shows the shoe heel connected to the creeper. Fig. 4 is a front end view of the creeper shown in Fig. 3 but omitting the shoe heel.

The shoe heel 6 is preferably formed of india rubber composition which is elastic, but it may be formed of leather or other material suitable for shoe heels. The creeper has a base plate 7, preferably triangular in form, and the front end of this plate has two ice spurs 8 bent downwardly at its angles, for engaging with the ice. A slot 9 is formed crosswise at the middle of the front part of the base plate, and the metal in front of the slot is bent downwardly. A flat bar 10 is slidable in the slot 9, and has a sharp hook-shaped lug 12 at its front end adapted to engage with the front end of the rubber heel. The plate or bar 10 has also a projection 14 at its rear end which is adapted to engage with any one of a row 40 of holes 15 in the base plate 7. A spur 16 is also secured to the base plate 7, and projects downwardly from its rear end portion, and is adapted to engage with the ice.

A lug 17 projects upwardly from the rear end of the base plate 7, and has an eye 18 at its top formed by bending its top portion rearwardly and downwardly in circular form.

The heel of the shoe is held between the lugs 12 and 17. The lug 12 may be formed on or rigidly secured to the base plate, but

it is preferably connected to it so that it can be adjusted and set at different distances from the lug 17. In order to force the heel into engagement with the lugs, a forked positioning lever 19 is provided. The forked portion of this lever is curved longitudinally so that it will fit snugly around the heel of the shoe when the device is in the position shown in Fig. 3. The lever has a crosspiece 20 at its middle part, which is pivoted loosely in the eye 18. The crosspiece is formed integral with the lever, and the metal of the eye is bent around the crosspiece in circular form. The front end portions of the forked lever have sharp edges 21 for engaging with the shoe heel, and its other end has a short handle 22 for operating the lever.

When the parts are in the positions shown in Fig. 1 the lug 12 is first adjusted to suit the size of the shoe heel, and is then locked to the base plate. The lug 12 is then placed against the shoe heel when the heel is in the position shown in dotted lines in Fig. 3. The handle of the lever is then pressed upwardly. This turns the positioning lever on its pivot, and forces its sharp edges 21 into the material of the shoe heel. This presses the lug 12 into the front side of the shoe heel and turns the shoe heel and presses it downwardly in contact with the lug 17 until the shoe heel is seated on the base plate.

The creeper is removed from the shoe heel by pressing the handle of the positioning lever rearwardly and downwardly from the position shown in full lines in Fig. 3.

What I claim is:

1. In an ice creeper, a base plate provided with ice spurs and having front and rear lugs for engaging a shoe heel, the rear lug having an eye at its top, and a forked lever having a cross bar in its fork which is pivoted in the said eye and having a handle at one end, said lever having also sharp portions at its forked end which operate to seat the shoe heel on the base and retain it there in contact with the rear lug when the handle is raised pivotally by hand past the said eye.

2. In an ice creeper, a base plate provided with ice spurs, said plate having a downwardly bent portion and a slot in its front part and a row of holes behind the slot and

having at its rear end a lug provided with an eye at its top, a plate slideable under the base plate in the said slot and having at its front end a lug for engaging with the shoe heel and at its rear end a locking projection for engaging with any one of the said holes, and a positioning lever pivoted in the said

eye and provided with a sharp portion at one end for engaging with the shoe heel and having a handle at its other end.

In testimony whereof I have affixed my signature.

DAVID O. SHIBLER.
